CLAIM

The ornamental design for a night vision camera, as shown and described.

DESCRIPTION

FIG. 1 is a front, top, and left side perspective view of a night vision camera showing my new design;

FIG. 2 is a back, bottom, and right side perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an enlarged portion view taken from portion labeled “9,” in FIG. 1;

FIG. 10 is an enlarged portion view taken from portion labeled “10,” in FIG. 2; and,

FIG. 11 is an enlarged portion view taken from portion labeled “11,” in FIG. 4.

The dashed-dot lines form the boundary of the enlarged portion views of FIGS. 9, 10 and 11 in FIGS. 1, 2, 4, 9, 10 and 11 and form no part of the claimed design. The even dashed broken lines shown in the drawings are included for the purpose of illustrating portions of the night vision camera that form no part of the claimed design.
